UNITED STATES PATENT OFFICE.

CHARLES A. TREMAIN, OF BELLINGHAM, WASHINGTON.

PHONOGRAPH TONE RECTIFIER AND AMPLIFIER.

Application filed January 10, 1922. Serial No. 528,159.

To all whom it may concern:

Be it known that I, CHARLES A. TREMAIN, a citizen of the United States, and a resident of Bellingham, in the county of Whatcom and State of Washington, have invented a new and useful Phonograph Tone Rectifier and Amplifier, of which the following is a specification.

My invention relates to improvements in tone rectifiers and amplifiers for phonographs, and the object of my improvement is to produce a simple and inexpensive device which when placed between a phonograph turntable and the record thereon will improve the reproduced tone both as to quality and volume.

I attain this object with the device illustrated in the accompanying sheet of drawings, in which Figure 1 is a plan view of my device, Fig. 2 is a side elevation of Fig. 1, and Fig. 3 is a plan view of a phonograph turntable and reproducer with my device in operative position thereon.

Similar characters refer to similar parts throughout. Certain parts are broken away to show other parts hidden thereby.

Broadly, my device comprises a thin, flat, sonorous body adapted to intervene between the turntable of a phonograph and the record thereon.

More particularly: A thin circular disc 4 has a central hole a^4 suited to pass over the central pin of a phonograph turntable. Radial loops 6, 6 are rigidly fastened in the periphery of disc 4 to lie in the plane thereof. Strings 8, 8 are stretched taut between the ends of loops 6 and the periphery of disc

4 and fastened thereto. A paper washer, one of which is shown at 5, is fastened to each side of disc 4. A serving of yarn is wound around the outer end of each of loops 6 at 7, 7. By preference I make disc 4 of metal, loops 6 of spring wire and strings 8 of thin piano springs. Wires 6 are soldered in saw kerfs in disc 4 and wires 8 are soldered in saw kerfs in disc 4 and also soldered to wires 6. To operate as intended wires 8 must be in a taut condition.

In Fig. 3 the tone reproducer of a phonograph is shown at 9, the turntable of the same at 10, a phonograph record at 11, the turntable pin at 12 and my device in operative position between said turntable and said record.

When constructed and used as shown and described, my device noticeably improves the quality and volume of the reproduced tones from the instrument.

Somewhat louder tones can be got when the serving of yarn 7 is not used and the record is allowed to bear directly on wires 6, but I prefer to use the yarn as shown.

Having thus disclosed my invention, what I claim is new and desire to secure by Letters Patent is,

In a phonograph tone improver in combination a metal disc having a central hole, a plurality of spring-metal loops fastened to said disk in the plane thereof, and a plurality of spring steel wires stretched taut between said disc and said loops and fastened thereto.

CHARLES A. TREMAIN.
